UNITED STATES PATENT OFFICE

2,289,369

HIGHWAY TRAFFIC SIGNAL

Frank Kinecannon, Jackson, Miss.

Application September 27, 1938, Serial No. 231,964

1 Claim. (Cl. 177—327)

The present invention relates to traffic signals for streets, highways, and the like and has for its principal object to provide a device of this character adapted for mounting at street intersections and embodying a hand movable around a dial simulating a clock, one-half of said dial comprising a green illuminated segment and the other half of the dial comprising a red illuminated segment arranged for opposite energization whereby the movement of the hand around the dial will indicate to pedestrians and traffic the approximate length of time remaining before a change will occur in the traffic signal.

A further object of the invention is to provide electro-magnetically controlled mechanism associated with the traffic signal for moving the hand in a step-by-step movement in a manner simulating the movement of the second hand of a clock.

A still further object is to provide a traffic signal of this character embodying a rectangular casing providing for right angle faces upon each of which one of the dials and hands is mounted and in which the hands at the respective opposite sides of the casing are arranged uniformly with respect to their associated illuminated dials to indicate identical signals for traffic moving in opposite directions.

A still further object is to provide a device of this character of simple and practical construction, which is neat and attractive in appearance, relatively inexpensive to manufacture and install in operative position and otherwise well-adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which:

Figure 1 is a perspective view of the hand operating mechanism.

Figure 2 is a transverse sectional view taken substantially on the line 2—2 of Figure 1.

Figure 3 is a front elevational view of the signal housing and

Figure 4 is a similar view showing a modified form of dial.

Figure 5 is a diagram of the electric circuit controlling the alternate energization of the red and green tubes and signals.

Referring now to the drawings in detail, wherein for the purpose of illustration I have disclosed a preferred embodiment of invention, the

numeral 5 designates a substantially rectangular frame supported in an upright position upon a standard or post 6, said frame embodying vertical sides 7, a top 8 and bottom 9. A vertical shaft 10 is journaled at its opposite ends in the upper and lower frame members 8 and 9 and upon said shaft is keyed a ratchet wheel 11 and a bevelled gear 12. The ratchet wheel 11 is adapted for actuation by a pawl 13 pivotally mounted upon a pair of spaced parallel arms 14, both of said arms being swingably supported upon a pin 15 secured in bosses 16 to one of the vertical frame members 7, the opposite end of said arm terminating in operative association with respect to a pair of electro-magnets 17 secured to the opposite vertical frame member 7.

Energization of the electro-magnets 17 will operate to attract the free ends of the arms 14 whereby the pawl 13 will rotate the ratchet 11 in accordance with such movement of the arms. The electro-magnets 17 are contained within an electric circuit 18 in which a circuit breaker (not shown) of conventional construction is also connected for controlling the electro-magnets from a remote point, said circuit breaker being of a type adapted to impart sixty impulses per minute, more or less, depending upon the speed desired for rotating the shaft 10.

A spring-pressed dog 19 is also mounted upon the pin 15 and having engagement with the ratchet wheel 11 to prevent reverse movement of said wheel. A coil spring 20 is interposed between a fixed extension 21 on the frame 7 and one of the arms 14 to move the free end of the arm out of engagement with the electro-magnets, when the latter are de-energized.

A bearing bracket 22 is secured to each of the vertical frame members 7 within each of which a shaft 23 is journaled, the inner end of said shaft having a bevel gear 24 keyed thereon for engagement with the bevel gear 12 and the outer ends of said shafts are provided with hands or pointers 25.

A pair of arms 26 extend horizontally from opposite sides of the lower frame member 9 at right angles thereto, each of said arms being provided with upstanding ends 27 and to which bearing brackets 28 are secured. Shafts 29 are journaled in each of said brackets, the inner ends of said shafts having a bevel gear 30 keyed thereon and positioned in engagement with the bevel gear 12 and the outer ends of said shafts have hands or pointers 31 secured thereto.

The frame 5 and mechanism carried thereby, except the hands 25 and 31, are enclosed within

a housing 32, said housing having right angle walls to the inner face of which the bearing brackets 22 and 28 are secured to support the respective hands 25 and 31 outwardly with respect to said housing.

To the outer surface of each of the walls of the housing 32 are secured a plurality of neon light tubes 33, said tubes being arranged in circular form separated at the tops and bottoms thereof and arranged to comprise a pair of concentric red light tubes 34 and a pair of green light tubes 35, said tubes cooperating to form a dial around which one of the hands is adapted to move. Above the dial is positioned a warning indicia 36 comprising the word "Stop," the letters of which are likewise formed of red neon light tubes and beneath the dial is positioned a warning indicia 37 comprising the word "Go" formed of green neon light tubes.

In the form of the invention illustrated in Fig. 4 of the drawings, portions of the outer semi-circular neon tubes forming the dials are offset as shown at 38 at regularly spaced intervals to simulate integrations.

As illustrated in Fig. 1 of the drawings the pair of hands at the respective opposite sides of the housing 32 are arranged opposite from the remaining hands in order that the hands at two sides of the housing will appear in association with the green neon light tubes while the opposite hand will appear in association with the red neon light tubes.

As shown in Figure 5 the "Stop" and "Go" portions of the signal are electrically connected in the circuit together with the red and green light tubes, respectively, in order that all of the related signal units will be simultaneously energized. Alternating current generator 39 supplies current for energizing the red and green tubes. A circuit breaker 40 actuated by motor 41 serves to turn the current through the red and green circuit alternately. Numerals 42 and 43 indicate transformers required to step the current up to the voltage necessary for neon tube illumination. Direct current flows from direct current generator 44 through circuit breaker 45 to magnet 46. Circuit breakers 40 and 45 are both operated by motor 41. Ratchet wheel 47 is merely a suggested means of operating circuit breaker 45.

It is obvious that the bevelled gear on the drive shaft of the signal must be larger than its intermeshing gears which turn the hand. Otherwise these five gears would interlock and would not

turn. For purposes of timing the ratio of the drive gear to the four hand gears is constructed two to one. Thus if a device similar to ratchet wheel 47 is used for circuit breaker 45, it must have half as many teeth as the ratchet wheel in the signal in order that one revolution of the circuit breaker ratchet will turn the hands one revolution. The making and breaking of the direct current circuit alternately magnetizes and demagnetizes electro-magnet 46 which operates the mechanism as described. Switches 48 and 49 operated by a common lever are used in the event of fire or other emergencies. It will be noted that this interrupts the operation of the mechanism and turns the current through all red neon tubing. It will appear apparent from the foregoing that a circuit breaker is provided which delivers current to the red neon tubing through half of the revolution of the hand and to the green neon tubing through the other half of the revolution of the hand and at the same time makes and breaks a direct current to the electro-magnet which furnishes the motive force for turning the aforesaid hand.

25 A brake device is employed for the shaft 10 to prevent accumulation of momentum which would tend to throw the several signals out of synchronization and comprises an arm 50 pivoted at one end on the pin 15 and provided intermediate its ends with a projection 51 having an arcuate face bearing against the collar 52 of the gear 12. The other end of the arm is yieldably held in braking position by a spring 53 mounted on a pin 54 secured to the frame member 7.

It is believed the details of construction and operation of the apparatus will be readily understood from the foregoing without further detailed explanation.

40 Having thus described the invention what I claim is:

45 In a traffic signalling device of a type having a plurality of faces arranged in the form of a square, a vertical post, a stationary frame supported thereon and including a vertical frame member positioned behind each face, a pointer swingably mounted on each frame member in front of each face, a vertical shaft journaled in the frame, gears operatively connecting the shaft with the pointers, and operating means for the shaft to provide a step by step movement of the pointers.

FRANK KINCANNON.
